UNITED STATES PATENT OFFICE

2,432,004

COOLANT PUMP

John De Witt Gray, Chicago, Ill., assignor, by
mesne assignments, to Gray-Mills Corporation,
Evanston, Ill., a corporation of Illinois

Application June 26, 1943, Serial No. 492,369

4 Claims. (Cl. 103—41)

1

This application relates to portable, fluid pumping apparatus and particularly to an improved, many duty pump which may be used in a recirculating system or as a convenient means for emptying one container and filling another.

The invention herein disclosed follows closely that described in applicant's copending application Serial No. 436,082 filed March 25, 1942. In that application, applicant illustrates a portable container with a removable lid having suspended from its under side a gear pump which will be submerged in fluid in the container when the lid is in closed position. A fluid delivery hose from the pump extends through the lid of the container and the delivery end or nozzle of this hose may be directed upon a cutting tool. The fluid so delivered may be caught in a pan and returned to the container wherein is mounted the gear pump. This portable recirculating system is used in machine shops for recirculating a fluid coolant from a source of supply to a tool and back to the source of supply.

The principal object of this invention is to modify the portable gear pump and container illustrated in applicant's copending application in such a way that it may perform an ordinary pumping operation consisting of emptying a drum of oil into any other suitable container. One of the features of the present invention is the provision of a flexible intake line to the inlet of the pump. By this arrangement, the flexible inlet line may be submerged in a container to be emptied and the delivery line may be directed to any other container or depository.

While it is rarely desirable in transferring a liquid from one container to another to control the rate of flow in the delivery line, it sometimes is desirable, and one of the objects of this invention is to provide a manual control for the volume output of the pump without necessarily introducing the pumped fluid into the container containing the pump. In the invention shown in the copending application, the flow of the outlet line is controlled by the expedient of bypassing any selected quantity of liquid from the delivery line back into the container from which it has been pumped. In the present invention means are provided where this may be done if desired or not. In the latter case, the fluid is bypassed back to the intake of the gear pump and not circulated back into the container at all.

In connection with this bypassing arrangement, one of the major objects of this invention is to provide a simple means for using the fluid in the container to prime the pump. These gear

2

pumps and more particularly the hose connections are not very tight and if the pump stands 24 hours without use, the lines will become sufficiently empty of fluid and filled with air so that the pump will not function unless it is primed.

A major object of this invention is to provide means for priming both the inlet and the outlet sides of the gear pump with fluid from the container by a simple manual operation. By this arrangement, if the level of the fluid in the container is above the pumping point by a distance greater than the distance from the fluid level to the point where the inlet line passes over the edge of the container, it will always be possible to quickly prime the pump. As a practical matter, however, the inlet hose is not primed in this way. Applicant provides a hole in the top of the lid through which the intake end of the flexible hose may be passed downwardly into the fluid in the container, and then the hose can be filled with fluid and the pump stopped. The flexible hose may then be withdrawn and its end placed in the container which is to be emptied and the pump started. This results in some complications if the fluids are different, as for example if the container to be emptied is filled with a cutting oil of one viscosity and the portable pump unit is filled with an oil of a different viscosity. In machine shops, however, while they endeavor to keep the oil separate, a little mixing does not cause any measurable harm.

These and such other objects as may herein-after appear are attained in one embodiment of the invention shown in the accompanying drawings comprising one sheet wherein:

Figure 1 illustrates applicant's portable pumping unit positioned between two containers; and

Figure 2 is a sectional view of applicant's portable container showing the conduits in the pump which make it possible to prime the pump.

Continuing to refer to the drawings and particularly to Figure 1, the numeral 10 generally identifies applicant's portable unit consisting of a container 12, a lid 14, an electric motor or other source of power 16 controlled by a switch unit 17, a flexible delivery hose 18 and a flexible intake hose 20. In the lid 14 is an opening 22 of a size sufficient to admit the end 24 of the intake line 20 while a second opening 26, depending from which is an inverted conoidal shaped screen 28 (see Figure 2), permits the insertion therein of a return hose line (not shown) from a catch pan disposed beneath a machine tool, as described in applicant's copending application.

Referring now to Figure 2, the intake line 20

feeds a duct 30 which in turn opens into the gear pump section 32, which need not here be described, other than to say that the pump is driven by a suitable power train from the motor 16. From the section 32 the oil is forced during operation into the delivery duct 34 and thence out the delivery hose 18. Connecting the delivery duct 34 to the delivery conduit 30 is a duct 36 which communicates with duct 34 by passageway 38 and with duct 30 by passageway 40. In vertical alignment with the passageway 38 is a valve 42 of the pin type which is positioned with respect to the general pump housing 44 by means of a threaded engagement between its lower threaded end 46 and a threaded shoulder 48. The lower end of the valve 42 may be caused to seat on a beveled shoulder 49 at the top of passageway 38 and close the same by rotating the rod 50 having a wing nut 52 at the upper end thereof.

It will be noted that the duct 36 by means of the passageway 54 opens into the inside of the container 12. Its inside outer end is threaded to receive a cap screw 56.

The remaining structure of applicant's portable gear pump need not here be described, as it is identical with the structure described in the copending application.

When it is desired to use the portable pump for handling one type of fluid, either for a recirculating operation or for a container emptying operation, the cap screw 56 will be removed.

Assuming first that it is desired to perform a recirculating operation, that is to say, an operation for delivering a coolant to a tool and thence returning the warmed coolant to the container for recirculating by the pump, the intake line 20 will have its end 24 positioned through the opening 22 in the pumping unit lid 14 so that it will occupy some position such as 60 in Figure 2. When the pump is started, fluid will be drawn from the container 12 into the inlet end 24 of the hose 20, thence outside the lid, thence back into the container to the duct 30. From thence, the fluid will pass through the gear pump, the duct 34 and out the delivery line 18. If the delivery line has its nozzle directed on some tool for cooling, ordinarily the coolant will be picked up by a pan drained by a flexible hose, the outlet end of which will be positioned in the opening 26 of the lid 14 and the fluid will pass through the strainer 28 into the container 12.

If it is desired to empty a large drum such as 62 in Figure 1 into a smaller container such as 64 or to fill the container 12 of the pumping unit 10, the end 24 of the intake line 20 will be placed in the container to be emptied and the valve 42 will be turned down until the passageway 38 is closed. It will be appreciated that during a container emptying operation, the full capacity of the pump ordinarily will be utilized. There will be no need to reduce the flow at the delivery point. When the valve 42 is in closed position, there is established a fluidtight connection from the intake hose 20 to the delivery line 18 and the container can be completely emptied. Moreover, if it is desired to empty the container 12, all that is necessary is to place the end 24 in position 60.

If it is desired to limit the flow in the delivery line 18 without employing a nozzle at the delivery end for restricting the flow, as by by-passing a quantity of fluid from the delivery side of the pump to the intake side without introducing fluid into the container 12, the cap screw 56 may be placed in position with the result that the pump will suck a given quantity of fluid from the inlet

line 20 and depending upon the opening between the valve 42 and the passageway 38, the pump will suck a quantity through the conduit 36 from the delivery side.

One of the most important functions of this arrangement is to prime the pump and this priming is done on both the inlet and outlet sides of the line. When the cap screw 56 is removed, if the pump loses its prime, all that is necessary is to open the valve 42. Under such circumstances fluid will enter the conduits 54 and 36, which are merely extensions of one another, and by the passageways 38 and 40 will enter the delivery conduit 34 and the inlet conduit 30. By placing the end 24 of the inlet conduit 20 in position 60, one is quickly able to fill the conduit 20 with fluid so that it may then be transferred to some other container for emptying the same.

Having thus described my invention, what I wish to patent and protect by United States Letters Patent is:

1. Portable pumping apparatus comprising a container, a lid therefor, a gear pump suspended from the under side of said lid for positioning within said container below a fluid level when the lid is in closed position, an inlet and an outlet on the pump, a conduit having one end in liquid tight engagement with said inlet and its other end outside the container, a conduit having one end in liquid tight engagement with said outlet and having its other end outside the container, and means for admitting fluid from the container to both the inlet and outlet sides of the pump concurrently whereby the pump may be primed.

2. Portable pumping apparatus comprising a container, a lid therefor, a gear pump suspended from the under side of said lid for positioning within said container below a fluid level when the lid is in closed position, an inlet and an outlet on the pump, a conduit having one end in liquid tight engagement with said inlet and its other end outside the container, a conduit having one end in liquid tight engagement with said outlet and having its other end outside the container, and means for admitting fluid from the container to both the inlet and outlet sides of the pump concurrently whereby the pump may be primed, said means being mounted on the lid and controllable from a point thereabove.

3. In a portable fluid pumping apparatus consisting of a container and a container lid having a pump mounted on the under side thereof, a horizontally disposed delivery line from said pump, directly thereabove a by-pass conduit opening into the interior of the container, a port having a vertically disposed axis connecting the delivery line and the by-pass conduit, an opening in vertical alignment with the port and connecting the bypass conduit to the inside of the container, and a valve positioned through said opening and seatable in said port, said valve being controllable from above the lid.

4. In a portable fluid pumping apparatus consisting of a container, a container lid, and a casting containing a pump suspended from the under side of the lid, a horizontally disposed delivery line in said casting, vertically thereabove a bypass conduit opening into the outside of the casting and also into the low side of the pump, a port having a vertically disposed axis connecting the delivery line to the bypass conduit, a threaded opening in the casting above and in alignment with the part and a rod threadably mounted in the opening and adapted to move inwardly of the

casting to close the port, said rod extending above
the lid.
